WENDELL WRIGHT, OF BLOOMFIELD, NEW JERSEY.

Letters Patent No. 84,042, dated November 10, 1868.

IMPROVEMENT IN SUSPENDER-FASTENINGS.

The Schedule referred to in these Letters Patent and making part of the same.

To all whom it may concern:

Be it known that I, WENDELL WRIGHT, of Bloomfield, in the county of Essex, and State of New Jersey, have invented a new and improved Suspender-Fastener; and I do hereby declare that the following is a full, clear, and exact description thereof, which will enable others skilled in the art to make and use the same, reference being had to the accompanying drawings, forming part of this specification.

This invention relates to a new and improved suspender-fastening, and is designed to supersede the ordinary flexible straps provided with button-holes to fit over buttons on the pantaloons, and retain the latter in a proper elevated state on the wearer.

The invention consists of metallic clamps connected with the buckles of the suspenders, in such a manner that they may be readily connected to and disconnected from the buckles, the clamps holding both pants and drawers in a proper elevated state.

In the accompanying sheet of drawings—

Figure 1 is a view of my invention shown applied or in use.

Figure 2, an enlarged vertical section of the same.

Similar letters of reference indicate corresponding parts.

A represents the buckle of a suspender, which is provided with a metallic pendent portion, *a*, bent in hook-form at its lower end, as shown at *b*; a spring or elastic plate, *c*, being attached to the upper part of *a*, extending down and pressing against the inner side of the upper part of the hook, as shown clearly in fig. 2, the whole forming a combined snap-hook and buckle.

B represents a clamp, or, in fact, two clamps, composed of two metal strips *d d*, placed side by side, and

bent in such a manner that the clamp portions with opposite oblique positions, as shown in fig. 1, the two strips, being connected at their central portions by a collar, *f*, to admit of the clamps being readily opened and closed. The inner surfaces of the strips *d d* have spurs or points *g* attached, as shown clearly in fig. 2, and rings *h h* encircle the clamps, in order to keep them closed or in contact with the pants and drawers, when fitted over the tops of the same, the spurs or points *g* penetrating the aforesaid garments.

These clamps are fitted on the snap-hooks of the buckles, and it is designed to let the clamps remain on the pants or drawers, the former being slipped off from the snap-hooks when the wearer wishes to take off the garment.

By this improvement, both the pants and the drawers may be properly held in an elevated state on the wearer, and the device is durable, there being no button-holes to tear out, nor buttons to become detached. The invention also may be constructed at a moderate cost.

Having described my invention,

I claim as new, and desire to secure by Letters Patent—

The double clamps *B*, having teeth on their inner faces, and provided with slides *h*, said clamps being hinged together by the collar *f*, and removably attached to the buckle *A* by means of a snap-hook, *a C b*, formed on the latter, all constructed and arranged substantially as herein shown and described.

WENDELL WRIGHT.
